UNITED STATES PATENT OFFICE.

FREDERICK LESEER, OF BROOKLYN, NEW YORK, ASSIGNOR TO BRIGHT STAR BATTERY COMPANY, A CORPORATION OF NEW YORK.

PORTABLE ELECTRIC LIGHT.

Application filed November 19, 1926. Serial No. 149,388.

My present invention relates to a new and improved form of portable electric light, commonly called a "flashlight".

In devices of this kind it has been common to vary the width of the angle of illumination by mounting the lens through which the light is projected upon a movable portion of the lamp and bringing about the desired effect by moving such lens toward or away 10 from the electric light bulb, according to the effect desired.

This has generally been accomplished by mounting the lens upon a screw cap on the front end of the flashlight, and turning the 15 cap one way or the other to vary the focus. In addition to this, every flashlight requires means for making and breaking the circuit to light or extinguish the lamp proper.

In former devices, every change of focus 20 has required the use of two hands. It is the principal advantage of the present invention that the adjustment of focus can be obtained by the use of the thumb or finger of one hand alone, and preferably by the same 25 movement that turns the light off and on.

My invention is illustrated in the accompanying drawings wherein Figure 1 is a view of my lamp in longitudinal section, Figure 2 is a similar view of the front end of the 30 same showing another position of the parts, Figure 3 is a similar view to Figure 2, showing still another position of the parts, Figure 4 is a transverse sectional view of my device, taken on the line 4—4 of Figure 2, and Figure 5 is a sectional view on the line 5—5 of Figure 1.

Broadly stated, my invention comprises a 40 movable incandescent lamp bulb and a stationary lens or reflector or (preferably) both for concentrating the light rays more or less. The bulb moves in such a manner with respect to the light concentrating means that the angle of light projection may be varied at will.

Preferably the construction is such that the same mechanical element is used to open and close the lamp circuit and to move the bulb.

In the drawing the usual outer casing is 50 shown at 10, and in the specific form shown, this casing is made of insulating material. The usual battery is shown at 11, and the zinc cup of the lowermost cell makes contact with the spring 12 on the screw cap 13

which holds the carbon terminals 14 in contact with the metal pin 15 on the transverse metal strip 16.

This strip 16 is carried by a core or body 17 of insulating material which slips into the usual front metal shell 18. This shell is 60 screwed onto the body 10, as shown and it carries the usual glass protector 19, which may or may not be a lens and is mounted on a thin metal frame 20 which screws down onto the shell 18.

At the front end of the body 17, and under the glass 19, is mounted the usual reflector 21, having a central aperture, as shown in Figure 1.

The center of the body 17 is bored to receive and guide a hollow reciprocating metal bulb-mounting 22, on one side of which is a rack 23, which engages with the teeth of the pinion 24. This pinion extends partly 70 outside of the shell 18, so that it can be revolved one way or the other by the thumb of a person holding the flashlight in his hand. This movement will, of course, cause the bulb-mounting 22 to move in or out on the longitudinal axis of the flashlight.

In order to give stability to the "off" or "dark" position of the pinion 24, it is provided with a shallow cavity 25 in its side. In the "off" position, shown in Figure 1, this cavity is engaged by the rounded end of a 80 pin 26, pressed forward by a pin 27, as shown in Figure 5. The pinion 24 is preferably made of insulating material, to avoid danger of short circuit.

The usual incandescent bulb 28 extends 90 through the opening in the reflector 21, and its outer filament terminal screws into the metal mounting piece 22.

The central filament terminal of the bulb 28 is kept constantly in electrical connection with the plate 16 by means of the spring 29 which is maintained in proper position by the pin 15. This keeps the central bulb terminal in constant electric connection with the carbon electrode of the battery 11.

Just above one side of the bulb mounting 22 when it is in the "off" position shown in Figure 1, is a pin 30 slidably mounted in a cavity in the body 17. This cavity is closed by a screw 31 which is constantly in contact with the metal shell 18. Between the screw 31 and the pin 30 is a spring 32 which normally presses the pin 30 into the

position shown in Figure 1, while permitting said pin to move back as shown in Figure 3, when the bulb mounting is lifted.

The shell 18 is kept constantly in electric connection with the zinc electrode of the battery through the spring 12, the screw cap 13 and a thin metal strip 33. Therefore, when the mounting 22 touches the pin 30, circuit is instantly closed through the filament in the lamp bulb 28.

To light the lamp, therefore, it is only necessary to revolve the pinion 24 with the thumb to move the bulb-carrying body 22 from the "off" position of Figure 1 to the first lighted position, shown in Figure 2. Here contact is made with the pin 30, and the lamp is lighted.

This contact is preserved however far forward the body 22 may thereafter be moved forward by revolution of the pinion 24.

Thus the lighted bulb may be moved into any desired position, from that shown in Figure 2 all the way to that shown in Figure 3. In this way the relation of the lamp to the reflector 21 and the glass 19 may be varied at will, and thus vary the focus without using two hands.

Various changes may be made in the structure of my device without departing from

the scope of my invention, which is not limited to the details herein shown and described.

What I claim is—

1. In a portable electric light, an exterior casing having a slot, a bulb-carrying element adapted to reciprocate within said casing and provided with a rack, a pinion engaging said rack and extending through said slot in convenient position to be operated by the finger and contact closing means adapted to operate when said bulb-carrying element is moved.

2. In a portable electric light, an outer casing, a concave reflector having a central opening carried by said casing, an insulating body having a bore registering with the opening in said reflector, a bulb-carrying element slidably fitting in said bore, a bulb on said element projecting through the opening in the reflector, a spring pressed electric contact piece arranged to be capable of motion through the side of said bore, and means for moving the bulb-carrying element past said contact piece while in contact therewith.

In testimony whereof I have hereto affixed my signature on this 1st day of November, 1926.

FREDERICK LESER.
